FIG. 5

UNITED STATES PATENT OFFICE.

GEORGE F. BLACK, OF BALTIMORE, MARYLAND.

COMBINED SASH HOLDER AND FASTENER.

1,358,611.

Specification of Letters Patent.

Patented Nov. 9, 1920.

Application filed May 13, 1920. Serial No. 381,140.

To all whom it may concern:

Be it known that I, GEORGE F. BLACK, a citizen of the United States, residing at Baltimore, in the State of Maryland, have 5 invented certain new and useful Improvements in Combined Sash Holders and Fasteners; and I do declare the following to be a full, clear and exact description of the invention, such as will enable others skilled 10 in the art to which it appertains, to make and use the same.

This invention relates to a combined sash holder and fastener.

The object of the invention is to provide 15 a novel device of this character which is of such construction that it will hold the window open when it is one position, and when reversed to another position, will retain the window in locked position, that is 20 when the window is closed.

Another object of the invention is to generally improve upon devices of this class by providing one of extreme simplicity, one 25 which is highly effective in operation, one which is easy to manipulate, one which will not mar or bruise the woodwork as the majority of devices of this class do, and one which is extremely inexpensive to both the manufacturer and user.

30 Other objects and advantages of the invention will be apparent during the course of the following description.

In the accompanying drawings forming 35 a part of this specification and in which like numerals are employed to designate like parts throughout the same:

Figure 1 is an elevational view of a device constructed in accordance with my invention, showing the same applied and 40 closing the position it takes when it is ineffective.

Fig. 2 is a view showing the position the device assumes when holding a window in the window in closed position.

45 Fig. 3 is a view showing the device reversed, which position it assumes to retain the window in closed position.

50 Fig. 4 is a sectional view taken on the line 4—4 of Fig. 3, looking in the direction of the arrows.

Fig. 5 is a view taken on the line 5—5 of Fig. 2.

Fig. 6 is a detail perspective view of a device constructed in accordance with my invention disclosing one method of making 55 the same.

Fig. 7 is a like view showing another method of making the device.

In the drawings for the purpose of illustration, I have shown a portion of a window 60 frame, designated by the numeral 1, and portion of a window which slides in the frame, being designated by the numeral 2. My improved device is to be applied on the window in such a position as to engage the 65 window frame.

The device comprises a flat metal triangular plate 3 provided with a centrally disposed slot 4 which extends from a point adjacent the base of the triangle, to a point 70 adjacent the apex thereof. In addition to this slot, the plate is further provided with a plurality of ears 5, two of which are at the corners of the plate, and the other of which is at the apex of the plate. Each 75 of these ears projects outwardly beyond the two converging edges of the plate, and the edge of each ear is rounded in the manner shown.

Carried by the two ears adjacent the base 80 of the plate, are cylindrical lugs 6 which serve a purpose to be described and also serve as knobs or handles, as will be herein-after more thoroughly set forth. Carried by the remaining ear is another lug 7 of 85 arcuate formation. These lugs in conjunction with the ears form a plurality of friction shoes which are spaced from one another and are designed to engage the window frame 1 in the manner shown. By this arrangement it is possible to reverse the plate 90 to either of the positions shown in Figs. 2 and 3, and in either of these positions a two-point contact will be had.

Emphasis is to be laid on this two-point contact feature because of the fact that it insures effective operation of the device. To describe this feature more thoroughly it may be said that because of this construction the friction shoes will obtain an effective grip on 95 the window frame regardless of whether or not there are slight irregularities on the frame. It may be stated that on some window frames there may be projections in

100

- the form of hardened paint, tacks, and the like, and if the edges of the plate were corrugated or smooth, an effective grip would not be had due to the fact that the 5 edge of the plate would not engage such irregularities but would merely slip over them and not take hold. With my construction this is not the case, because the friction shoes extend outwardly from the 10 divergent edges of the plate, consequently the shoes will at all times obtain an effective grip whether or not there are irregularities on the window frame. This is a feature of construction to be carefully considered.
- 15 Close examination of the disclosure of the device will disclose the fact that the curved working surfaces of the lugs 6 and ears 5 are flush with one another. By "working surfaces" I mean the surface of these parts 20 which frictionally engage the window frame. Due to this manner of constructing the friction shoes, it will be seen that the shoes cannot mar or bruise the woodwork as the majority of devices of this class do.
- 25 This is another feature of construction to be carefully considered. The lugs 6 in addition to forming a part of the friction shoes, serve as knobs or handles, by means of which the plate is reversed from the 30 position shown in Fig. 2 to the position shown in Fig. 3.

In the construction of my device so far described, it will be seen that the plate 3, ears 5, and the lugs 6 and 7 are made of 35 a single casting. This is one way of making the device, but I do not desire to limit myself to this method of construction, because it may be made in the manner shown in Fig. 7. By referring to this figure it 40 will be seen that the device is stamped from sheet metal. For the sake of convenience and clearness of description, I will place the same reference characters on this form of my invention as are employed to designate the several parts of the form of my 45 invention shown in Fig. 6.

In use, the plate 3 is fastened upon the window frame 2 by means of a screw or the like 8, the latter extending through the slot 50 4 in the plate. In its normal position, the device will take the position shown in Fig. 1, wherein the screw 8 is at one end of the slot 4. It is for this reason that I form the lug 7 of arcuate formation. To explain, it 55 is to be said that by so forming the lug, a clearance space for the head of the screw 8 will be had. If it is desired to hold the window in an elevated position, one of the friction shoes, which serve as handles, may be gripped and the plate moved to the position, shown in Fig. 2. This may be done by merely pushing the plate upwardly from the position shown in Fig. 1. When in this 60 position the slot 4 is inclined toward the window frame, and should the window move

downwardly, the screw will ride against the outer edge of the slot 4 and force the friction shoes into effective engagement with the window frame, thus holding the window in an elevated position. It may be stated 70 here, that to insure that the proper wedging action will be obtained, it may be necessary to hold the device against movement with one hand while the window is moved slightly downward with the other hand. This practice will prevent the device from dropping, due to its weight, to an ineffective position, as it might do if it were not held in the foregoing manner. To retain the window in locked position when it is closed, it is 80 obvious that it is only necessary to reverse the position of the device from that just described to the position shown in Fig. 3, wherein the base of the triangular plate is swung upwardly. When in this position 85 the slot 4 will be inclined at a different angle, consequently if an attempt is made to raise the window, the screw acting in the slot will force the friction shoes into effective engagement with the window frame 90 and prevent the window from being opened.

A device constructed in accordance with my invention will be found extremely novel and advantageous, due to the fact that the friction shoes will always obtain an effective 95 grip on the window frame regardless of whether or not the latter has any irregularities thereon. It may be stated at this point, that in many cases there is a weather strip secured on the window frame, consequently 100 there is a slight space, in some cases, between the weather strip and the window. Because of this, it is necessary that the plate be of sufficient thickness to prevent it from working into this space and not obtaining a 105 grip. With my construction I overcome any such circumstances because the lugs 6 and 7 project far enough beyond the plate to prevent this. My device is extremely 110 simple and easy to manipulate, and is inexpensive.

I am aware that devices of similar construction to mine are patented and are in use, but I do not know of any device that possesses all the constructional advantages 115 that my device does.

A careful consideration of the foregoing description will enable persons skilled in the art to which this invention relates, to obtain a thorough understanding of the same, 120 therefore, further description is deemed unnecessary.

I claim:

A combined sash holder and lock comprising a flat metal triangular plate provided with a centrally arranged slot which terminates adjacent the apex and base of the plate, the latter being further provided at its two corners and point with ears which extend outwardly beyond the two converg- 125 130

ing edges of the plate, the edges of said ears being curved, and a laterally extending lug carried by each ear, the working face of each lug being also curved on a line to correspond with the curvature of the edges of the ears, said lugs and ears forming spaced friction shoes which are adapted to engage the win-

dow frame and hold the window closed or in an elevated position substantially as described.

In testimony whereof I have hereunto set my hand.

GEORGE F. BLACK.
